DESIGN FOR A TOWEL RACK

Bertis F. Hamilton, Columbus, Ind.

Application October 5, 1936, Serial No. 65,164

Term of patent 3½ years

To all whom it may concern:

Be it known that I, Bertis F. Hamilton, a citizen of the United States, residing at Columbus, Bartholomew County, Indiana, have invented a new, original, and ornamental Design for a Towel Rack, of which the following is a specification, reference being had to the accompanying drawing, forming part thereof.

Fig. 1 is a top plan view of the towel rack showing my new design; Fig. 2 is an elevation of the towel rack shown in Fig. 1; and Fig. 3 is a fragmental front elevation of the towel rack on an enlarged scale showing the center portion of the towel rack as it would appear when viewed at line 3—3 in Fig. 1.

I claim:

The ornamental design for a towel rack, as shown.

BERTIS F. HAMILTON,
